UNITED STATES PATENT OFFICE.

BENJAMIN A. WELDS, OF JACKSON, MICHIGAN.

FENCE-LOCK.

SPECIFICATION forming part of Letters Patent No. 286,752, dated October 16, 1883.

Application filed February 2, 1883. (Model.)

To all whom it may concern:

Be it known that I, BENJAMIN A. WELDS, of Jackson, county of Jackson, and State of Michigan, have invented an Improvement in 5 Fence-Locks, of which the following is a specification.

This invention has relation to improvements in worm rail-fences; and it consists in securing its rails together at each intersection by 10 wires, the wires being applied from the same side of the fence by stapling one end of each to a lower rail of the fence and the other end to the second rail of the same panel on the opposite side thereof, as will be hereinafter more 15 fully set forth and claimed.

In the accompanying drawing, which forms a part of this specification and shows my invention in perspective, A A represent the sections of a rail-fence built up in the ordinary manner. To bind the corners securely together, one end of the wire B is looped and one of the top rails let down parallel with the fence, as shown at a. An ordinary fence-staple is then driven through the looped end of the wire into the second rail from the top, 20 near the corner of the upper end of the top rail and on the opposite side of the fence, as at b. The wire is then brought over the top rail, another staple driven into one of the lower rails, and the lower end of the wire B looped to the staple, when, by lifting the top rail to its place on the fence, the corners are bound 25 securely together. This binding being done at each of the intersecting corners, a solid and compact fence is constructed, which will resist breaching stock and heavy winds. Should 30 the fence settle to such an extent that the lock is not effective, it can readily and easily be rebound by letting the top rail down, as when 35 the lock was put on, and slipping the wire toward the long end of the rail on top, when, by 40 putting the rail back to place, as tight and strong tension is given to the wire as when first put on.

45 I am aware that worm-fences have been

locked at the corners by wire loops passed around the ends of the rails and wedges driven between the rails; and I am also aware that such wire loops have been tightened to clamp the rails together by twisting their upper ends 50 with the top rails of the fence. The objections to the first construction are, that it is difficult to take down and put up the section of the fence without special instruments, and the wedges have to be cut, making an additional expense, and to the second construction 55 that the wire loop cannot be tightened excepting by taking the fence partially down; and the objection to my former patents numbered 220,892, October 21, 1879, and 237,220, February 1, 1881, as well as the two above-mentioned 60 patents, is that they take more than as much again wire to obtain the same results that the single wire and staples do. This is also the only lock of the wire construction that 65 can be locked from one side of the fence. All the locks above referred to have to be locked from both sides of the fence at every alternate corner. By this device more than one-half of the material is saved, and one-half the labor 70 required to put up the former locks will put up the staple and wire lock. My invention overcomes former objections.

Having described my invention, what I claim is—

A worm rail-fence having its rails secured together at each intersection by wires D, the wires being all applied from the same side of the fence by stapling one end of each to a lower rail of the fence and the other end to the 80 second rail of the same panel on the opposite side thereof, substantially as shown and described.

In testimony whereof I hereunto affix my signature in the presence of two witnesses.

BENJAMIN A. WELDS.
